CLAIM

The ornamental design for a electronic device case, as substantially shown and described.

DESCRIPTION

FIG. 1 is a front right perspective view of a first embodiment of a electronic device case showing my new design in a closed position;

FIG. 2 is a front right perspective view thereof in an open position;

FIG. 3 is a rear left perspective view thereof in a closed position;

FIG. 4 is a left side elevation view thereof in a closed position;

FIG. 5 is a bottom plan view thereof in a closed position;

FIG. 6 is the rear left perspective view shown in FIG. 3 with the addition of environmental broken lines depicting a pair of headphones; the broken lines forming no part of the claim;

FIG. 7 is a rear left perspective view of a second embodiment of a electronic device case showing my new design in a closed position, wherein the front view of the second embodiment in an open position is as shown in FIG. 1; the pairs of counterpart jagged, broken lines form no portion of the claimed design and the portions between such pairs of counterpart jagged, broken lines are broken away to disclose indeterminate radial dimension of the back plate;

FIG. 8 is a left side elevation view thereof in a closed position;

FIG. 9 is a rear left perspective view of a third embodiment of a electronic device case showing my new design in a closed position, wherein the front perspective view of the third embodiment in an open position is as shown in FIG. 1; the pairs of counterpart jagged, broken lines form no portion of the claimed design and the portions between such pairs of counterpart jagged, broken lines are broken away to disclose indeterminate radial dimension of the back plate;

FIG. 10 is a left side elevation view thereof in a closed position;

FIG. 11 is a rear left perspective view of a fourth embodiment of an electronic device case showing my new design in a closed position, wherein the front perspective view of the fourth embodiment in an open position is as shown in FIG. 1; pairs of counterpart jagged, broken lines form no portion of the claimed design and the portions between such pairs of counterpart jagged, broken lines are broken away to disclose indeterminate radial dimension of the back plate; and,

FIG. 12 is a left side elevation view thereof in a closed position.

The broken lines in the drawings, indicating that no particular shape is being claimed, represent environmental subject matter, and form no part of the claimed design. The pairs of counterpart jagged, broken lines form no portion of the claimed design and the portions between such pairs of counterpart jagged, broken lines are broken away to disclose indeterminate radial dimension of the back plate.
